UNITED STATES PATENT OFFICE.

HERVEY H. MCINTIRE, OF SOUTH BEND, INDIANA.

ELECTRICALLY-INFLUENCED TIMING DEVICE.

Application filed November 22, 1920. Serial No. 425,930.

To all whom it may concern:

Be it known that I, HERVEY H. MCINTIRE, a citizen of the United States, residing at South Bend, in the county of St. Joseph and State of Indiana, have invented certain new and useful Improvements in Electrically-Influenced Timing Devices, of which the following is a specification.

The invention relates to time indicating devices for determining the duration of exposure of photographic prints, and is more especially adapted for use in connection with photographic printing machines.

The invention has for its object to provide a device of this character for use in establishments which employ electric lamps for exposing prints which are on commercial circuits, the voltage of which fluctuate more or less in accordance with the load on the circuits at different times, as influenced, for instance, by the cutting in and out of the line of motors for driving heavy machinery, elevators, etc. The primary object is to provide a circuit controlled timing device whereby, after establishing the proper period of exposure to produce the desired tone value in a print under normal condition or voltage of the circuit, successive prints may be easily produced having the same tone value. By the fluctuation of the voltage, at which time the rays of the lamp become either weaker or stronger, exposure of the print for the same period as under normal voltage would result in either an under or over exposure in so far as obtaining uniform tone values in successive prints is concerned. The invention thus contemplates the provision of a time indicating device controlled by the lamp circuit, whereby any fluctuation of the voltage affecting the power of the lamp from normal will influence proportionately the interval between the indicated time periods, whereby the requisite quantity of actinic rays for obtaining successive uniform prints may be measured out by the same number of indicated time periods.

Assuming for example that the indicated time periods would be ten in number, as by the tapping of a bell, which may be the equivalent of ten seconds, is found to be the proper duration of exposure for obtaining the desired tone value in a print, and it is desired to produce many prints of uniform tone value. If in process of exposing the successive prints the voltage should drop and the power of the lamp should drop so

as to actually require twenty seconds of exposure to obtain the same tone value, the timing device, owing to being directly influenced by the voltage, would operate but half as fast, so that by relying on the same number of indicated periods the same quantity of actinic rays of the lamp would be measured out, and uniformity of tone value obtained as under normal voltage. The same condition would obtain if the voltage should rise above normal, in which case the timing device would operate more rapidly, and there would be a proportionately shorter interval between the indicated periods.

Once the proper duration of exposure is ascertained under normal conditions the same number of time periods indicated by the device will represent the proper duration of exposure for obtaining uniformity of tone value in successive prints regardless of the variation in the power of the lamp as affected by the fluctuation of the voltage.

A further object is to provide a circuit making and breaking device comprising a frame having mounted thereon a shaft on the ends of which discs are secured, one of said discs being linked to a solenoid core and adapted to be partially rotated by said solenoid which is in a light circuit. The disc is provided with a lug which contacts with an arm of a pivoted contact member and adapted to engage said arm and cause the pivoted contact member to move from side to side for making or breaking the circuit. The disc on the other end of the shaft is provided with weight members for varying the speed of rotation thereof, and also provided with spring arms playing between stops and forming means for reversing the rotation of the disc.

With the above and other objects in view, the invention resides in the combination and arrangement of parts as hereinafter set forth, shown in the drawings, described and claimed, it being understood that changes in the precise embodiment of the invention may be made within the scope of what is claimed without departing from the spirit of the invention.

In the drawings:

Figure 1 is a front elevation of the device.

Figure 2 is a side elevation.

Figure 3 is a rear elevation.

Referring to the drawings, the letter A designates a switch used for opening and closing a circuit A'. Upon the closing of

the switch A the circuit A', which is a commercial circuit having a fluctuating voltage, the lamp B comes on for exposing a print. The circuit A' being closed, the solenoid C 5 is momentarily energized, the current passing through the lead D, the fixed contact E and a make and break switch F, which switch has its contact point G in electrical connection with the hook I through a wire 10 H, then through the switch controlling spring J, which has one of its ends connected to the hook I and its other end connected to the hook I' of the bracket K, said bracket K having connected thereto a lead 15 H which leads to the solenoid C. The other side of the solenoid C is in circuit with the light circuit A' through the lead wire L'. As the solenoid is energized, its core is 20 drawn in and imparts a limited rotative movement in one direction to the disc M. The disc M is provided with an inwardly extending pin N, which pin during the movement of the disc M engages the finger O of the pivoted switch member F, thereby causing 25 said member to move on its pivotal point F' to the dotted line position shown in Figure 1, and as the pivotal point F' passes through the pivotal points of the spring J, the finger O strikes a bell P, each tap of 30 which represents a period of time. It will be seen that the pivoted switch member will be held in either closed or open position by the spring J, as said spring J passes to either 35 side of the pivotal point F'. Disc M is carried by a shaft M', which is rotatably mounted in a supporting bracket C' and is connected to the core C² by means of a link C³. Secured to the other end of the shaft M' is another disc Q, on which disc 40 is pivotally mounted an adjustable arm R, the outer end of which is bent to overlie the periphery of the disc Q and extend inwardly sufficiently on its rear side to allow the arm R to be securely clamped in any position 45 on the disc, after it has been adjusted, by means of a set screw S, which binds the outer end of the arm on the edge of the disc. Said arm has secured thereto as at R' spring 50 fingers S' and S², which fingers engage stops T and T'. Stop T is a stationary stop and is carried by the support C' and stop T' is an adjustable stop and is carried by a pivoted arm T² by the movement of which arm T², the relation of the stop to the spring 55 arm S² may be varied. As the solenoid is momentarily energized and the core C² pulled downwardly therein, the finger S' contacts with the stop T, thus arresting the movement of the disc Q, and in so doing 60 said spring finger S' becomes flexed and the solenoid deenergized by the contact of the pin N with the finger O of the pivoted switch F, which is thrown to the dotted line position shown in Figure 1. The reflex action 65 of the spring finger S' then causes the

disc Q to reverse its movement and the finger S² moves around until it strikes the stop T', at which time the spring finger S² is flexed and then sets up a reflex action so that, under the influence of the solenoid and the action of the spring fingers, the disc Q is oscillated, and each period of time in such movement is indicated by the striking of the bell. It will be seen that as the disc Q is oscillated in the direction of the arrow A, under the reflex action of the spring finger S', that the pin N will engage the finger O' of the pivoted switch member F and cause the contact point G to again engage the fixed contact E, thereby momentarily closing the circuit. The pivoted arm R is provided with an inwardly and outwardly adjustable weight R² and an inwardly and outwardly adjustable weight U is provided at the opposite side of the disc Q, by means of which weights and the adjustable stop T', the device may be made to operate slow or fast according to the voltage of the current employed as may be required for the best operating speed. 90

Assuming that it would require under normal conditions of voltage a period of exposure of the print equal to and indicated by ten time periods represented by a striking of the bell in order to produce and reproduce a certain tone value. In order to obtain such tone value, the sensitized or developing paper must be influenced by exposure to the actinic rays of the light of a given quantity, and which is found to be measured out in said time period. As the actinic rays given off by the light would vary in quantity within a given time owing to a fluctuation of the voltage increasing or decreasing the power of the light, it is evident that, unless such indicated time periods would also vary by a faster or slower operation of the timing device, that the desired quantity of actinic rays would not be accurately measured or indicated, and an over or under exposure would result. As the device in its operation is influenced by the same current and voltage as the lamp, the time periods will fluctuate with the fluctuation of the voltage, and uniform results can be substantially obtained. Heretofore it could not be understood why paper coated with the same emulsion and given the same time exposure by the use of a time piece would not produce uniform tone value, because it was not recognized that the power of the lamp varied with the voltage, and it is for this reason that time pieces and timing devices heretofore provided are not practical and have not given the desired result. 110

The invention having been set forth what is claimed as new and useful is:—

1. The combination with a photographer's exposure light circuit having a fluctuating 130

voltage, of means for controlling said circuit whereby successive circuit closing operations will fluctuate in time according to the fluctuation of the voltage of the circuit, 5 and signalling means for indicating the successive circuit breaking operations.

2. The combination with a lighting circuit having a fluctuating voltage, of a circuit maker and breaker therefor, said circuit 10 maker and breaker comprising a frame having rotatably mounted therein a shaft, discs carried by the ends of the shaft, one of said discs being provided with a link connection with a solenoid, said solenoid being adapted 15 to partially rotate said disc, a pivoted switch carried by the frame, means carried by the disc for moving said switch into and out of operative position with a contact, said contact and solenoid being in circuit with the 20 lighting circuit, adjustable spring arms carried by the disc at the other end of the shaft, said spring arms playing between stops, means for adjusting said spring arms to different positions, said spring arms forming 25 means for reversing the direction of rotation of the disc, and adjustable weight members carried by one of the discs for adjusting the time of oscillation.

3. In a lighting circuit having a fluctuating 30 voltage, a circuit maker and breaker comprising a frame, a shaft rotatably mounted in said frame and provided with discs, a solenoid carried by the frame and having a link connection with one of the 35 discs, a pivoted switch carried by the frame and provided with fingers, a lug carried by one of the discs and adapted to engage said fingers for swinging said switch out of engagement with the contact and into engagement 40 with a bell, spring means for holding said switch in both positions, stops carried by the frame adjacent the other disc and spring arms carried by said last named disc and playing between said stops and forming 45 means for reversing the direction of rotation of the discs.

4. In a lighting circuit having a fluctuating 50 voltage, a circuit maker and breaker comprising a frame, shaft carried rotatable discs supported in the frame, a solenoid for imparting a partial rotation to said disc, a contact and alarm disposed above one of said discs and spaced apart, a pivoted spring controlled switch disposed between 55 the contact and the alarm, means carried by the solenoid controlled disc for shifting the switch into engagement with the contact or with the alarm, adjustable spring arms carried by the other disc, said spring arms 60 playing between stops carried by the frame and forming means for reversing the direction of rotation of the disc, means for varying the distance between said stops for adjusting the time of reversal and adjustable

weight members for additionally varying 65 the time of reversal.

5. In a lighting circuit having a fluctuating voltage, a circuit maker and breaker comprising simultaneously rotatable discs, a solenoid for imparting a partial rotation to 70 said discs, a spaced contact and signal adjacent one of said discs, a pivoted spring controlled switch disposed between the contact and signal, means carried by one of the discs for throwing said switch into engagement with the signal and into engagement with the contact and spring means carried by one of the discs for reversing the direction of rotation of the disc after signalling 75 periods and circuit closing periods.

6. In a lighting circuit having a fluctuating voltage, a circuit maker and breaker comprising simultaneously rotatable discs, a solenoid for imparting a partial rotation to 80 said disc, a contact and signal adjacent one of the discs and spaced apart, a pivoted switch between the contact and signal, spring means for normally holding said switch either in engagement with the contact or with the signal means carried by one 85 of the discs for shifting the switch from the contact to the signal on a partial rotation of the disc in one direction, spring means carried by one of the discs and playing between stops and forming means for reversing the direction of rotation of the discs after a signalling period and after a circuit 90 closing period, and adjustable weight members for varying the time of rotation of the disc.

7. In a lighting circuit having a fluctuating voltage, a circuit maker and breaker comprising a pivoted switch, said switch being disposed between a contact and a signal, spring means for normally holding the switch either in engagement with the contact or the signal, means for shifting said switch from engagement with the contact and into engagement with the signal, vice versa, said means comprising a rotatable disc having thereon means for engaging the switch upon the oscillation of the disc, spring arms rotatable with the disc and playing between stops and forming means for reversing the direction of oscillation of the disc and weight means for varying the speed of rotation of the disc, for varying the time of shifting of the pivoted switch.

8. In a lighting circuit having a fluctuating voltage, a circuit maker and breaker comprising a pivoted switch disposed between a contact point and a signal and held in engagement with one or the other by means of a spring, means for shifting said switch from the contact to the signal or vice versa, said means comprising a rotatable disc, electrical means for imparting a partial rotation of the disc in one direction,

said disc being provided with means for shifting the switch for engagement with the signal, and out of engagement with the contact, spring arms carried by a second disc and playing between stops, one of said spring arms being positioned to reverse the direction of rotation, the other spring arm forming means for reversing the direction

of rotation of the disc at the other end of its partial rotation, means for adjusting said stops in relation to each other, and weight means for varying the speed of rotation of the disc during its oscillation.

In testimony whereof I affix my signature.

HERVEY H. McINTIRE.
